UNITED STATES PATENT OFFICE.

JOHN F. O'CONNOR, OF CHICAGO, ILLINOIS, ASSIGNOR TO WILLIAM H. MINER, OF CHICAGO, ILLINOIS.

FRICITION-BUFFER FOR RAILWAY-CARS.

1,146,344.

Specification of Letters Patent. Patented July 13, 1915.

Application filed February 10, 1913. Serial No. 747,221.

To all whom it may concern:

Be it known that I, JOHN F. O'CONNOR, a citizen of the United States, residing at Chicago, in the county of Cook and State of Illinois, have invented a certain new and useful Improvement in Friction-Buffers for Railway-Cars, of which the following is a full, clear, concise, and exact description, reference being had to the accompanying 10 drawings, forming a part of this specification.

My invention relates to friction buffers, the same being particularly adapted for employment upon railway passenger cars.

15 The object of my invention is to provide a friction buffer of a strong, efficient and durable construction.

In the accompanying drawings forming a part of this specification Figure 1 is a sectional view the upper half of which above the section line 2—2 thereon is taken on the section line 1—2 of Fig. 2 and the lower half below said section line 2—2 is taken on the line 1—3 of Fig. 2. Fig. 2 is a plan view 20 partly in horizontal section on line 2—2 of Fig. 1. Fig. 3 is a plan view partly in horizontal section of the compression resisting member showing the position of the parts when the spring cap engages the wedge member. Fig. 4 is a plan view partly in horizontal section of the compression resisting member showing the position of the parts when in full compression. Fig. 5 is a perspective view of the main buffer spring seat.

25 Fig. 6 is a perspective view of the wedge. Fig. 7 is a perspective view of one of the friction shoes. Fig. 8 is a perspective view of one of the anti-friction rollers. Fig. 9 is a perspective view of the compression resisting member. Fig. 10 is a perspective view of the evener. Fig. 11 is a perspective view of a supplemental spring washer.

In the drawings 12 represents a portion of the front end frame of a railway passenger car, 13 the buffer cage or frame, 14 a steel floor plate of the vestibule of the car, 15 the buffer plate, 16 the buffer bar, 17 the foot or chafe plate, 18 the side stem, 19 the side stem spring, 20 the main transom casting.

30 The numeral 21 represents the compression resisting member. The buffer cage or frame 13 forms a part of the framework of the car, and is furnished with supports 22 and 23 to receive the buffer bar 16, and with 35 a chamber 24 beneath the vestibule plate 14

of the car to receive the compression resisting member 21, and with the saddle 25 and the supporting plate 26 for holding in position the compression resisting member. The compression resisting member 21 comprises a spring cap 27, main buffer springs 28, 28, friction mechanisms 29, 29, the shell 30, supplemental springs 31, and the evener 32.

The shell 30 is provided with the friction 40 chambers 33, 33, preferably two in number, and arranged side by side. Each friction chamber is open at both ends, and each chamber contains a friction mechanism 29. The shell also contains a plurality of supplemental spring chambers, preferably two in number, the said chambers being arranged adjacent to the friction chambers, and one at either side of the same, and preferably forwardly extended to form a space between 45 them in which the spring cap 27 operates.

The spring chambers each contain a supplemental spring 31, and are each preferably open at the forward ends 34, 34, and closed at the rear ends by the preferably integral plate 35, each of said plates having a perforation 36 for the passage of a bolt 37, which extends through the said chamber and connects the washer or movable spring seat 38 with the evener 32. The said bolt is 50 adapted to compress the supplemental spring, (through which it passes), between the washer 38 and the plate 35 on rearward movement of the evener.

The shell 30 is rearwardly provided with 55 a recess 39 within which the evener 32 operates. The said evener extends substantially across the width of the said recess, and is forwardly provided with a plurality of bosses 40, equal in number to the friction 60 chambers, each of which is adapted to enter a friction chamber and engage the friction mechanism 29 therein. The friction mechanism in each friction chamber comprises friction shoes 41, preferably three in number, and adapted to engage the adjacent boss 40 of the evener 32, and a wedge 42.

In preferable construction the friction 65 shoes 41 are in annular arrangement, and provided with an inner wedging face 43 and an outer frictional face 44 adapted to frictionally engage the inner friction face 45 of the friction chamber. The wedge is 70 provided with wedging faces 42^a, there being one for each friction shoe. Between 75

each wedging face 42^a of the wedge and a wedging face 43 of the adjacent shoe is interposed an anti-friction roller 46. The wedge 42 is forwardly provided with an extension or wedge stem 47, which is preferably integral with the wedge. An opening 48 passes through the wedge and stem to receive the connecting rod 49, which extends therethrough, and through the evener at its 10 one end and the spring cap at its other end.

The spring cap 27 is provided with a plurality of main spring chambers 50, preferably two, there being one opposed to each friction chamber. Within each spring 15 chamber of the spring cap there is extended from the forward end a hub 51, within which is provided the recess 52 to receive the head 53 of the connecting rod 49. The recess 52 is of sufficient length to permit the 20 movement of the head of the connecting rod therein in the reciprocating movement of the spring cap. The connecting rod is provided at its rear end with the nut 54, the said connecting rod serving to keep the spring 25 cap and its contained parts, the friction mechanism, within the friction chambers, and the evener in assembled position. Within each spring cap 27 is a main buffer spring 28, which is seated at its forward end around 30 the hub 51, and at its rear end against a main buffer spring seat 55. Each spring seat 55 comprises a rim 56 adapted to engage the forward end 57 of the surrounding wall 58 of a friction chamber, and is also 35 provided with an opening 59 adapted to receive the stem 47 of the wedge 42 therethrough. The main spring 28 for a portion of its length surrounds the stem 47 of the wedge 42, and is adapted to be compressed 40 against the face 60 of the spring seat 55. The spring seats 55 may be varied in longitudinal dimension, and the length of the main buffer springs proportionately varied, as may be desired.

45 I prefer to construct my buffer with a space when the parts are in normal position between the evener and the adjacent spring chamber, as indicated by the numeral 63, Fig. 2, to allow for any wear. Each supplemental spring is preferably of greater 50 compression resisting capacity than one of the main springs.

The buffer bar 16 at its rear end 62 engages the spring cap 21. On rearward movement of the buffer bar the main buffer 55 springs are compressed between the spring cap and the spring seat 55 immediately in front of the friction mechanism until each hub 51 engages the alined stem 47 of the 60 wedge 42. Thereupon the wedges move rearwardly, spreading the friction shoes 41 of the friction mechanisms, and forcing them rearwardly. The friction shoes through 65 their engagement with the evener 32 and its connection with the bolts 37, 37 almost

simultaneously with the beginning of the wedging action between the wedges and shoes cause the supplemental springs 31 each to be rearwardly compressed between the spring chamber at the rear end and the 70 washer 38 at the forward end. Meanwhile the main buffer springs are further compressed against the spring seats 55.

It will be apparent that the frictional release of the friction mechanism is absolutely 75 certain in this device regardless of the length of movement of the friction mechanism within the friction chambers, because the main buffer spring is seated independently of the friction mechanism. The friction 80 shoes in release action are always brought immediately to their normal position from any possible position in their frictional movement regardless of the length of said movement, and are therefore always 85 when in service in position for immediate frictional resistance. On release movement of the parts the supplemental springs instantly draw the evener to normal position, thus returning the friction shoes and wedging 90 members to normal position within the friction chambers. Meanwhile the main buffer spring is expanding, the greater portion of its expansive movement taking place, however, after the wedge stem and spring 95 cap have disengaged, which disengagement occurs instantly with the return of the friction members to normal position.

The stem 47 of the wedge 42 as an integral member of the wedge permits an action in 100 which the wedge is never loose, and in which its wedging faces are each always in the same relative position to each of the adjacent wedging faces of the friction shoes, and thereby the antifriction rollers are always 105 held in taut position, and in the same relative position to each other.

I claim:—

1. In a friction buffer in combination, a shell, friction chambers, and spring chambers within the shell, the spring chambers being at the sides of the friction chambers friction mechanism in the friction chambers, springs in the spring chambers, means connecting the said springs and friction mechanism, a main spring, a spring cap, the main spring being seated between the shell and spring cap, and the spring cap being adapted to engage the friction mechanism on partial compression of the main spring. 110

2. In a friction buffer, a buffer bar, a spring cap engaging therewith, springs within the spring cap, a shell, friction chambers within the shell, friction mechanism in the friction chambers, springs at the sides 115 of the friction chambers, and means connecting said springs with the friction mechanism.

3. In the cushioning member of a friction buffer, a shell, spring chambers and friction 120

chambers in said shell, supplemental springs within the spring chambers and friction mechanism within the friction chambers, a spring cap, main springs between the spring 5 cap and shell, means connecting the friction mechanism to the supplemental springs, the said friction chambers being arranged side by side, and the spring chambers being arranged at either side of the friction chambers.

4. In a friction buffer, a buffer bar, a spring cap, a shell, a pair of friction chambers in twin arrangement in said shell, friction mechanism in said friction chambers, springs between the spring cap and shell, and supplemental springs at the sides of the friction chambers, and an evener connecting the friction mechanism with the supplemental springs.

5. In a friction buffer, in combination, a buffer bar, a spring cap, a shell, a pair of friction chambers side by side in said shell, said friction chambers open at both ends, a spring chamber at either side of the friction 25 chambers, friction mechanism within the friction chambers, springs within the spring chambers, an evener, means for connecting said evener to the supplemental springs, bosses on said evener, said bosses adapted to enter the friction chambers and engage the friction mechanism, and main springs, said main springs being seated between the spring cap and shell.

6. In a friction buffer, the combination

with a buffer bar and a spring cap, of a shell 35 having friction chambers, spring chambers, and an evener chamber therein, springs in the spring chambers, friction mechanism in the friction chambers, an evener in the evener chamber, springs between the spring 40 cap and shell, and means for engaging the spring cap and friction mechanism, the said evener engaging the friction mechanism, and having means connecting it to the springs in the spring chambers.

7. In a friction buffer, in combination, a buffer bar, a spring cap, a shell, a plurality of friction chambers in said shell, springs at either side of the friction chambers and substantially parallel therewith, a space between said springs and in front of the friction chambers adapted to receive the spring 50 cap, means connecting said springs with the friction mechanism, and springs seated between the spring cap and shell.

8. In a friction buffer, in combination, a buffer bar, a spring cap, a shell, friction chambers in said shell, friction mechanism in said chambers, further chambers at the sides of the friction chambers, compression 60 resisting mechanism in said chambers, means connecting the mechanism in all said chambers, springs seated between the spring cap and shell.
